(57) **CLAIM**

The ornamental design for a bottle, as shown and described.

DESCRIPTION

FIG. 1 is a top, front, and right side perspective view of a bottle showing my new design, a top, a rear, and left side perspective view being identical except for the threads;

FIG. 2 is a top plan view thereof; and,

FIG. 3 is a front elevation view thereof, the rear elevation view, right side elevation view, and left side elevation view being identical except for the threads.

The broken lines shown in the drawings are included for the purpose of showing environmental structure that forms no part of the claimed design.
